KNOCKDOWN GLOBULAR SHELL

Erwin Raisz, Cambridge, Mass., assignor to Global Press, Inc., New York, N. Y., a corporation of New York

Application September 1, 1944, Serial No. 552,251

7 Claims. (Cl. 35—46)

1

The present invention is concerned with knock-down globe-like structures particularly of the type useful for geographical or astronomical globes.

It is among the objects of the invention to provide a globe-like hollow structure, built from a series of absolutely flat blanks of sheet material and without resort to implements, or to fastening appliances such as nails, rivets, staples or to adhesive, but which may be assembled by hand, by direct interlock of the constituent blanks to each other and which in assembled relation is sufficiently rugged for practical purposes and not apt to come apart even under fairly rough handling.

The accompanying drawings in which is shown one of various possible embodiments of the several features of the invention,

Fig. 1 is a side elevation of the globe, according to the present invention,

Fig. 2 is a fragmentary view on a larger scale of a portion of the globe as viewed from the interior.

Figs. 3 and 4 are fragmentary sectional views taken on line 3—3 and 4—4 respectively of Fig. 2, and

Fig. 5 is a plan view of a sheet, showing the entire set of strips making up the globe-like structure.

Referring now to the drawings, the globe-like structure, as best shown in Fig. 1 is made up of a sequence of segmental bands 10, 11', 11² and 12', 12² the lateral edges of which are in substantially abutting relationship as at b, the circles of abutment lying in the enveloping geometrical globe indicated in dot and dash lines and to which the globe-like structure described is an approximation.

As shown, each of the segments is of frusto-conical form, the smaller of the segments 12 being on a more shallow cone, that is, one with a larger apex angle than the segments 11 of larger diameter. The median segment 10 is preferably a cylindrical band as shown, that is, a frusto-conical band of zero apex angle. At one, or if desired, at each of the polar regions a closure cap 13 is affixed at its edge to the smaller periphery of the extreme frusto-conical segment 12.

While the globe-like structure may be made of a larger number of narrower segments, so as to approximate even more closely the conformation of a perfect sphere, it is sufficient for practical purposes to conform the globe of the five segments shown in Fig. 5, with one or two of the end caps 13.

In the geographical application shown, the segments may be identified as follows: segment 10 as the Torrid Zone segment; segments 11' and 11²

2

as the Temperate Zone segments; segments 12' and 12² as the Frigid Zone segments. This terminology is used in the specification and certain of the claims merely for convenience, but it will be understood that the circles of contact as at b between consecutive segments are not necessarily along those parallels of latitude which define the demarcation between the respective geographical zones above identified.

10 In the preferred embodiment the globe-like structure is made up entirely of strips of flexible sheet material. While in certain applications, it may be made of sheet metal, it is preferred for most purposes to make it of fairly stiff paper, preferably of flexible paper board, which while limber has sufficient stiffness. In a preferred embodiment shown the Torrid Zone segment 10 is a generally rectangular band of length substantially equal to the equatorial periphery of the globe, and of width, illustratively shown in the drawings as of 30 degrees, that is, of one-twelfth its length.

The strips making up the Temperate Zone bands, i. e., the strips 11' and 11², constitute each 25 a sector of an annulus as shown. Each is illustratively of a width of 30 degrees, corresponding to the width of band 10 and is struck on a radius readily determined, so that when closed into the frusto-conical band form, it will fit into the geometrically spherical enveloping form suggested in Fig. 1. The larger outer or convex edge 15 of each Temperate Zone segment strips 11' and 11² is, of course, equal to the length of the Torrid Zone strip 10.

30 Similarly each strip 12' and 12² making up a Frigid Zone segment is a sector of an annulus, struck on much smaller radius, and extending for much more nearly the complete periphery than do sectors 11' and 11². Each of sectors 12' and 12² 40 when closed forms a frusto-conical Frigid Zone segment, with the larger base formed by convex edge 16, equal in length and periphery to the smaller or concave base 17 of the Temperate Zone segment. The polar cap 13 is of diameter or periphery to fit the aperture defined by the smaller or concave base 18 of the Frigid Zone segment 12'.

45 While the ends of each strip may be attached together by any suitable means, to form the corresponding cylindrical or frusto-conical segment, as the case may be, it is preferable to provide a unitary dove-tail tongue 20 at one end of each of said strips and complementary extension tongues 21' and 21² at the opposite end defining therebetween an undercut slot or gate 22 for ac-

commodating the corresponding dove-tail tongue 20.

For connecting together the consecutive segments, each segment strip is provided at each side thereof with a sequence of lateral dove-tail tongues 23 unitary with and in the plane of the strip. Desirably, though not necessarily, each dove-tail tongue has a root of width equal to 10 degrees of longitude, and the roots of consecutive tongues are spaced by interval of 10 degrees of longitude as shown. The dove-tail tongues of consecutive segments are intermeshed at the inner face of the globe-like structure as best shown in Fig. 2. Thus, as shown, the consecutive segments will abut at edgewise as at 24 and 25 and are held in assembled relation by the intermeshing dove-tail tongues.

The north polar disk shown likewise has dove-tail tongues 23 thereabout, which intermesh with the corresponding dove-tail tongues 23 on the associated smaller base 13 of the frigid zone segment 12'. It will be understood that the opening 27 at the South Pole could be used for mounting the globe-like structure upon a pedestal or other suitable support, or if desired, it could be closed by a south polar plate, similar to the plate 13 above described.

It will be understood that the various strips from which the globe is to be constructed may all be imprinted with their appropriate map segments (not shown in Fig. 5), upon a single sheet 30 of paper board, as shown in Fig. 5, from which the several strips 10, 11', 11², 12', 12² and 13 may be cut out by scissors or, if desired, the sheet may be impressed with tear lines as suggested at 31 to facilitate direct removal thereof from the carrying sheet 30. For assembly, each strip is formed into its ring by connecting the dove-tail tongue 20 at one end to the corresponding gate 22 at the other. The dove-tail tongues 23 at the sides of the strips are readily intermeshed at the interior of the structure in the manner above described, care being taken, of course, to bring the respective segments into proper register peripherally for building up the globe-like structure.

The dove-tail tongues 23 will not only lock the segments against direct separation and against relative rotary displacement but will also maintain the contiguous edges of consecutive segments against relative tilting and they assure accurate edge to edge alignment. Preferably the strips are so imprinted that at least some of the lateral joints are staggered with respect to the others as best shown in Fig. 2. The structure is mechanically strong, since each segment, especially those that are frusto-conical, withstands substantial compressive strain and the correlation of the segments results in a truss-like reinforcement along each diameter. The structure is sufficiently rugged to permit relatively rough handling without injury thereto or coming apart. It is understood of course that the edges of the segments may, if desired, be made to extend parallel to meridians, rather than to the equator, if desired.

The term "knock-down" as applied to the globe-like structure is intended to define the relationship whereby the globe may be built up from flat strips, as shown, and may be disassembled into flat strips for convenience of storage or shipment. The term "knock-down" is not intended to exclude the possibility however of stapling, gluing, or otherwise securing the parts formed as

shown in Figs. 1 and 2 into a permanent structure, if desired.

While the invention has its preferred applicability to geographical globes or to astronomical globes, it will be understood that it is also useful for other purposes, as for instance, for lamp shades or ornamental displays.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A hollow, knock-down globe-like structure of sheet material, comprising a median hollow band flanked at each of its sides by a sequence of frusto-conical bands, said bands being releasably interlocked in a self-sustaining structure, the junction lines between consecutive bands lying substantially in the enveloping geometrical spherical surface.

2. A hollow, knock-down globe-like structure of sheet material, comprising a median hollow band flanked at each of its sides by a sequence of frusto-conical bands, said bands being releasably interlocked in a self-sustaining structure, the junction lines between consecutive bands lying substantially in the enveloping geometrical spherical surface, and a cap plate interlocked with the free edge of at least one of the extreme frusto-conical bands.

3. A hollow, knock-down globe-like structure, composed of flat strips of flexible sheet material, each forming an approximation to a segment of a globe surface, the ends of each strip being connected together to form the segment, the various segments being in laterally abutting relationship, the lines of abutment being on circles of the enveloping geometrical sphere, each strip having lateral dove-tail tongues unitary therewith and in the plane thereof, the dove-tail tongues of contiguous segments intermeshing at the inner surface of the globe-like structure.

4. A hollow-knock-down globe-like structure comprising a median cylindrical band flanked at each of its sides by a sequence of frusto-conical bands, consecutive bands being laterally in edge to edge abutting relationship, the various boundary lines of said bands extending as circles in the enveloping geometrical spherical surface, each of said bands being composed of a flat strip of flexible sheet material, relatively stiff thereacross, each having lateral dove-tail tongues unitary therewith and in the plane thereof, said tongues of the consecutive segments being intermeshed at the interior of the structure.

5. A hollow, geographical knock-down globe-like structure, comprising an equatorial cylinder band and duplicate sets of frusto-conical bands forming segments abutting in substantially edge to edge relationship at opposite sides of the cylindrical band, a polar disk abutting the edge of the extreme frusto-conical band, the various bands and the disk being of diameters such that the abutting circular lines are all inscribed in the surface of the enveloping geometrical sphere, each of said segments and said disk having dove-tail tongues laterally protruding at one side thereof in the plane thereof and intermeshed

with those of the adjacent band at the inner face of the structure.

6. A hollow, geographical knock-down globe, composed of wholly flat sheets of flexible paper board including a cylindrical Torrid Zone band, a series of sectors of annuli, forming a pair of frusto-conical Temperate Zone bands and a pair of frusto-conical Frigid Zone bands, the larger base of each of the Temperate Zone bands being equal in circumference to that of the Torrid Zone band and the larger base of each of the Frigid Zone bands being equal in circumference to that of the smaller base of the Temperate Zone bands, the abutting demarcation lines between the respective bands comprising circles in the surface of the enveloping geometrical sphere, and a polar disk closing the smaller base of at least one of the Frigid Zone segments, each of said segments having unitary with the lateral edges thereof a sequence of dove-tail tongues, the tongues of each segment intermeshing at the inner face of the globe-like structure with the complementary tongues of the contiguous segment.

7. A knock-down self-sustaining globe-like structure comprising a plurality of initially flat pieces of sheet material including a rectangular sheet, a plurality of sectors of annular sheets, and a generally circular cap sheet, said rectangular sheet having means for securing the ends thereof together to form a cylindrical shell, the annular segment sheets having like means to form frusto-conical shells, the larger base of the largest shells being substantially equal in periphery to that of the cylindrical shell and the larger base of the next largest segmental shells being substantially equal in periphery to the smaller base of the largest frusto-conical shells, the cap disk being of periphery substantially equal to that of the smaller base of the smallest frusto-conical shell, each segmental unit having dove-tail tongues unitary therewith, protruding from the lateral edges thereof and in the respective planes thereof, the dove-tail tongues of the contiguous shells being interlocked in the interior of the structure.

ERWIN RAISZ.
